PLURAL COMPARTMENT REFRIGERATION APPARATUS

Harold W. Schaefer, Philadelphia, Pa., assignor to Philco Corporation, Philadelphia, Pa., a corporation of Pennsylvania

Continuation of application Serial No. 324,713, December 8, 1952. This application February 25, 1953, Serial No. 338,673

6 Claims. (Cl. 62—117.3)

1

This invention relates to refrigeration apparatus, being particularly concerned with plural compartment refrigerators of the type in which it is possible to maintain the several compartments under different temperature conditions. More specifically the invention has to do with refrigerators of the above-mentioned kind, in which provision is made for varying the relative sizes of the compartments as, for example, by varying the ratio of freezer volume to total storage volume, the present disclosure being a continuation of the subject matter described and claimed in my co-pending application bearing Serial No. 324,713, filed December 8, 1952, now abandoned.

Broadly, it is an object of my invention to make it possible to vary the relative sizes of the compartments in the simplest and most expeditious manner, and to adjust the refrigerating system in accordance with the volumetric relation of the compartments in order that each compartment may be maintained within predetermined, optimum temperature ranges.

The apparatus of my invention is particularly featured by the fact that the greatest possible degree of freedom in variation in volumetric ratio is provided and, in fact, the relative volumes of two compartments may be varied to such an extent that the entire cabinet functions as a freezer chest, or, alternatively, the entire space within the cabinet is available for use at relatively high temperatures, such for example as are required for the storage of fresh foods. Accordingly it is an object of the disclosed invention to provide a refrigerator in which the entire space within the cabinet may be operated either: at a low temperature, for example, at a sub-zero temperature; or at a relatively high temperature, for example the temperature adapted for the storage of fresh foods; or under conditions such that any predetermined part of the cabinet volume is maintained at a low temperature, the balance then being maintained at the higher temperature.

Further, my invention has as an object the provision of apparatus of the above-mentioned kind, in which all that is required to effect temperature adjustments necessitated by variation of the relative sizes of the compartments, is to position within the cabinet the partitioning means which is employed to divide the cabinet space into the sub-compartments desired.

To achieve the foregoing general objectives the apparatus of this invention, briefly described, comprises a cabinet provided with partitioning means movable to adjust the relative volumes of the two compartments which lie to either side of said means, together with a refrigeration system which includes a plurality of evaporator portions disposed along the length of the

2

cabinet, the apparatus further including means, responsive to placement of the partitioning means within the cabinet, to control the temperatures maintained at the several evaporator portions and therefore within the two compartments. In a preferred embodiment of the invention the said portions or sections of the evaporator structure are connected in series with suitable refrigerant circulating means, through the agency of a plurality of restricting devices interposed between said sections and effective, adjustably, to control the temperatures at the several evaporator sections in accordance with the selected volumetric ratio of the two compartments. Preferably, although not necessarily, the evaporator sections are controlled in such a way as to cause one of the compartments to be maintained at temperatures suitable for storing frozen foods, and to cause the other of said compartments to be maintained at temperatures suitable for the storage of fresh foods. As stated above the flexibility of the apparatus is also such that the entire cabinet may, selectively, be maintained at either the higher or the lower temperature.

The manner in which the objects and advantages of my invention may best be achieved will be fully understood from a consideration of the following detailed description taken together with the accompanying drawing, the single figure of which is a somewhat diagrammatic illustration of a preferred embodiment of the invention.

Making detailed reference to the drawing, it will be seen that the invention is therein illustrated as embodied in apparatus including an insulated enclosure designated, generally, by the reference numeral 10, this enclosure, for example, comprising the cabinet structure of a refrigerator of the household or domestic type. Partitioning means shown at 11 extends horizontally through the compartment, this partitioning means being of material of low thermal conductivity and being selectively disposable at various other locations within the compartment, as is represented by the broken line indications appearing at 11a and 11b. Any suitable means may be employed to support the partition within the cabinet, for example simple pins of the type shown may be utilized for this purpose, and it will be observed that the partitioning means may be disposed at any one of the illustrated elevations, or it may be removed entirely from the cabinet. The partition divides the space within the cabinet into upper and lower compartments and, with the partition in the position shown in full lines, a relatively small compartment 12 lies thereabove, whereas a larger compartment, shown at 13, comprises that portion of the total cabinet volume which lies be-

low the partition 11. As will be understood from the drawing, and without further description, disposition of the partition at either of the positions shown at 11a and 11b results in varying the volumetric relation between the two compartments 12 and 13.

Preferably, compartment 12 is maintained at a relatively low temperature, for example a sub-zero temperature, and compartment 13 is maintained at a relatively high temperature, for example a storage temperature in excess of the freezing point of water. The apparatus is, as will later appear, automatically operable to maintain the desired temperatures within the two compartments, regardless of the selected ratio of freezer volume to total storage volume. Further, if the partition 11 be completely removed from the cabinet, the entire refrigerator is conditioned for automatic maintenance of either the higher or the lower temperature mentioned, depending upon the adjustment of a "cold" control to which further reference will be made hereinafter.

To achieve operation of the kind described and, specifically, to provide for automatic maintenance of the space within the refrigerator at the desired, pre-selected temperatures, a novel refrigeration system is provided. This system comprises a refrigerant circulating device and suitable evaporator means including sections spaced along the length of the cabinet 10. In the embodiment illustrated the refrigerant circulating device takes the form of a condensing unit including a motor-compressor 14 and a condenser 15. Evaporator sections 16, 17, 18 and 19, are arranged in heat exchange relation with spaced portions of the cabinet structure, and all of the aforesaid elements are connected in series flow circuit through the agency of refrigerant flow conduits including a suction line 20 and a continuously open restricted connection of the capillary tube type, shown at 21.

As will now be understood, control of evaporator sections 16 and 19, and consequent maintenance of desired temperatures within the compartments 12 and 13, is accomplished in the simplest possible manner. Specifically temperature control is accomplished in response to the very movement of partition 11 which determines the relative sizes of the two compartments. To this general end auxiliary restricting devices 23 to 25, inclusive, are provided, as are by-pass conduits 27 to 29, flow through each of the latter being under the control of valve devices shown at 27a, 28a and 29a. As will later appear, the several valve devices are controlled by switches illustrated at 31 to 33, each switch including a plunger disposed for co-operation with the partition 11 at one of its illustrated locations. Each of the valve devices may be placed across the line "L" by suitable actuation of its associated switch, as is apparent from the drawing. Similarly, and in accordance with known practice, the compressor 14 is energized through a switch device 34 responsive to temperatures prevailing at the upper evaporator section 19.

Flow through the by-pass conduits may be considered to be the normal condition of operation, that is, the valves 27a to 29a are of the normally open type. Any of the valves may be closed by depression of the plunger of the associated switch, and this latter action takes place in response to placement of the partition at the level of said associated switch. Under the illustrated condition, that is, with the partition 11 disposed at its uppermost location, the plunger of switch device 33 is

depressed by the partition and valve 29a is therefore placed across the line "L" and remains closed. Valves 27a and 28a remain open under this condition and, as will be understood by those familiar with the art to which this invention pertains, evaporator sections 16, 17 and 18 (disposed below partition 11 and restrictor 25) are all maintained at substantially the same temperature. By virtue of closure of valve 29a, and consequent inclusion of the auxiliary restrictor 25 in the circuit, the three sections disposed below the partition are maintained at a pressure and temperature higher than that prevailing at the upper evaporator section 19. By suitable design of auxiliary restrictor 25 it is possible to maintain a considerable temperature differential between section 19 and the other sections of the evaporator, that is, to operate the compartment 12 at a desired temperature lower than the temperature maintained within compartment 13.

If it is desired to increase the low temperature storage volume, as compared to the total storage volume, the partition may be disposed at either of the elevations indicated at 11a and 11b and, 25 assuming that the partition be disposed at the location identified at 11a, valve 28a is closed with the result that auxiliary restrictor 24 is included in the circuit, the other auxiliary restrictors remaining substantially by-passed. Under such 30 conditions the evaporator sections 16 and 17 will be maintained at the higher temperature mentioned, whereas the evaporator sections 18 and 19 will be maintained at a lower value, and corresponding higher and lower temperature conditions of refrigeration prevail within the two compartments defined by the partition. It will be understood without further description that the restrictor and by-pass arrangement 23-27 is controllable in precisely the same manner, mere 35 placement of the partition at location 11b being sufficient to cause the upper three-quarters of the cabinet to function as a freezer and the lower quarter to serve as a refrigerator.

As indicated above, if it is desired to utilize 45 the entire cabinet at either the higher or the lower temperature, the partition is removed from the cabinet and, as a consequence, each of the valves 27a, 28a and 29a remains open. Under such a condition all sections of the evaporator operate at substantially the same pressure and temperature and all parts of the cabinet are therefore maintained at the same temperature.

Since it is possible to operate the entire cabinet 50 under a relatively low temperature condition, the capacity of the condensing unit is such as to enable it to maintain the entire volume of the cabinet at the lower temperature mentioned. If this condition is met, it is readily possible to achieve the various intermediate temperatures contemplated. As indicated above, cycling of the compressor is controlled from the upper evaporator section 19 and, when the temperature in all or the greater part of the cabinet is at the higher value, the operating time of the unit, on 55 a percentage basis, is relatively short. When all or most of the volume within the cabinet is maintained at the lower temperature, the percentage running time of the unit is increased. Preferably the control 34 is of the known Sylphon bellows type and, as such, is provided with a knob or the like, shown at 34a, through the agency of which it is possible to vary the "cut-in" and "cut-off" temperatures, to achieve either the 60 higher or the lower temperature throughout the 65

entire cabinet, as desired, and with the partition removed as aforesaid.

From the foregoing description it will be understood that by the present invention there is provided novel and improved refrigeration apparatus making it possible to vary the relative sizes of two refrigerated compartments and, concurrently, to adjust the refrigerating system in accordance with the volumetric relation of the compartments, whereby to maintain each compartment within a predetermined, optimum temperature range. The invention is featured by the ease with which temperature adjustments may be made, the necessary adjustments taking place automatically in response to establishment of the desired volumetric ratio.

The apparatus is useful for a variety of purposes being capable of serving as a freezer, as a refrigerator, or as equipment having provision for both such services within the same cabinet.

While the refrigeration system is illustrated diagrammatically, it is to be understood that the various evaporator sections could either be disposed within the storage area, or could be arranged in heat exchange relation with exterior surface portions of the cabinet inner liner member. For most purposes the latter arrangement is preferable. Also, in the broader aspect of the invention, it will be understood that the by-pass conduits may be controlled by the use of apparatus other than that specifically illustrated herein. For example it is possible to utilize valves having a lever or plunger extending into a position to be actuated by the partition structure, rather than electrically controlled valves of the kind shown. It will be understood, however, that the invention contemplates such changes and modifications as come within the scope of the appended claims.

I claim:

1. In refrigeration apparatus, a cabinet, a movable partition which may, selectively, be disposed at various locations within the cabinet to provide a pair of sub-compartments which may be adjusted as to volumetric ratio, evaporator means including a plurality of evaporator portions arranged in heat exchange relation with the said pair of compartments, said portions being selectively operable at higher or lower refrigerating temperatures, and control means disposed to be actuated by said partition at its various locations and effective to cause operation of said evaporator portions at either the higher or the lower refrigerating temperature in accordance with the position of said partition within the cabinet, disposition of the partition at any selected location within the cabinet actuating said control means in such manner that evaporator portions lying to one side of said partition are maintained at the higher refrigerating temperature and evaporator portions lying to the other side of said partition are maintained at the lower refrigerating temperature.

2. Apparatus in accordance with claim 1, and further characterized in that said control means includes a plurality of restrictors each disposed in circuit between a pair of adjacent evaporator portions, and in which apparatus said control means further includes means for by-passing said restrictors selectively in accordance with the position of the partition within said cabinet.

3. Apparatus in accordance with claim 2, and in which said by-passing means includes a plurality of switch devices effective to control flow of refrigerant through said by-passing means,

said switch devices being disposed for operation by said partition, selectively, when the latter is disposed at the several locations which it may occupy within the cabinet.

5 4. In refrigeration apparatus, a cabinet, partitioning means selectively disposable at various locations within the cabinet to divide the space therein into a pair of sub-compartments which may be adjusted as to volumetric ratio, cabinet 10 cooling means comprising elements including refrigerant circulating apparatus, a main restrictor, and a plurality of evaporator portions each carried by wall structure of said cabinet and arranged in heat exchange relation with a corresponding part of the length of the cabinet, all of the aforesaid elements being connected in series flow circuit, a plurality of auxiliary restricting devices each of which is disposed in the circuit between a pair of adjacent evaporator portions, means for by-passing said auxiliary restricting devices, and means for disabling said by-passing means whereby to include said auxiliary restricting devices, selectively, in the circuit, said last means being cooperable with said partitioning means to include in the circuit a different auxiliary restricting device for each of the several positions which said partitioning means may occupy within the cabinet.

30 5. In refrigeration apparatus, a cabinet, means providing for division of the space within the cabinet into a pair of sub-compartments which may be adjusted as to volumetric ratio, cabinet cooling means comprising elements including refrigerant circulating apparatus, a main restrictor and a plurality of evaporator portions, all of said elements being connected in series flow circuit, a plurality of auxiliary restricting devices each of which is disposed in the circuit between a pair of adjacent evaporator portions, and means operable upon adjustment of the volumetric ratio of said sub-compartments to provide for selective by-passing of said auxiliary restricting devices whereby to modify the cooling effect of said evaporator portions in accordance with the volumetric ratio of said sub-compartments.

45 6. In refrigeration apparatus, a cabinet, a movable partition which may, selectively, be disposed at various locations within the cabinet to provide a pair of sub-compartments which may be adjusted as to volumetric ratio, a heat exchange 50 system including a plurality of evaporator portions arranged in heat exchange relation with said pair of compartments, said system being selectively operable to maintain higher or lower refrigerating temperatures within said pair of compartments, and means situated at the said various locations and actuatable by said partition to control said system, disposition of the partition at any selected location within the cabinet actuating said control means in such manner that the compartment lying to one side of said partition is maintained at the higher refrigerating temperature and the compartment lying to the other side of said partition is maintained at the lower refrigerating temperature and regardless of the volumetric ratio between said compartments.
